UNITED STATES PATENT OFFICE.

HARRY LERNER, OF NEW YORK, N. Y.

DESIGN FOR A DISH MOUNTING OR HOLDER OR SIMILAR ARTICLE.

Application filed January 16, 1922. Serial No. 225. Term of patent 3½ years.

To all whom it may concern:

Be it known that HARRY LERNER, citizen of the United States, and resident of the city of New York, county of Kings, and State of New York, has invented a new, original, and ornamental Design for Dish Mountings or Holders or Similar Articles, of which the following is a specification, reference being had to the accompanying drawing, forming part thereof, in which—

Fig. 1 is a perspective view of a dish mounting or holder embodying my new design with a dish in position therein; and

Fig. 2 is a view showing the decorative element on which the design is based.

Referring to the drawing, in particular to the features that are most prominent, it will be seen that the design is comprised of a plurality of decorative elements such as shown in Fig. 2.

I claim:

The ornamental design for a dish mounting or holder or similar article as shown and described.

HARRY LERNER.
